METHOD OF BURNING POWDERED FUEL

Application filed March 6, 1925. Serial No. 13,467.

My invention relates to a method of burning powdered fuel and more particularly to a method of burning such fuel safely and with a flame close to the burner and to the construction of the fuel burner and the associated furnace parts through which the pulverized fuel is introduced into the heating zone of the furnace.

In furnaces of this type, a mixture of air and powdered fuel is introduced into the combustion chamber and there fired. There are two main types of burner employed for this purpose, one in which the fuel and air are completely mixed before introduction into the furnace and the other in which a jet of powdered fuel having insufficient air for perfect combustion is introduced into the furnace and there permitted to intermingle with larger quantities of air.

It has been found that the density of the fuel and air mixture plays an important part in determining the rate of flame propagation throughout the dust cloud. As shown by experiments, the greatest rate of flame propagation of powdered coal and air mixtures is obtained when from 80 to 100 cu. ft. of air is supplied per pound of coal. This ratio holds constant over a considerable range of coal and is not greatly changed by variations in the ash or moisture contents. On the other hand, the amount of air which gives the greatest rate of flame propagation is not sufficient for perfect combustion of the fuel under the normal furnace operating conditions. For this purpose it is required that the volume of air necessary for complete combustion of the coal range from 160 to 200 cu. ft. of air per pound of coal, this volume of course depending largely on the chemical analysis of the coal and the amount of impurities present.

The burner system commonly used at present is that in which the full amount of air is mixed with the fuel before it is introduced into the furnace, and this amount of air is sufficient for complete combustion of the fuel. Hence as above explained, there is too much air present in the mixture for rapid propagation of the flame, and there is a tendency for the flame to be drawn out

into a long cloud of burning material hence it is difficult to get the flame to start anywhere near the nozzle of the burner thereby wasting considerable furnace space. If the rate of movement of the fuel and air were slowed down to get the flame near the burner, there would be grave danger of the flame striking back into or through the burner.

If the other system is used whereby a rich mixture of coal and air is introduced at one portion of the furnace and secondary air is introduced at another point, then rapid ignition may be expected due to the rapid flame propagation in the rich mixture, but combustion cannot be completed until all the secondary air has come into contact with all of the fuel. This system results in the formation of a long flame the length of which depends upon the time taken to thoroughly combine the secondary air and the fuel. It, however, is difficult, in the average furnace construction, to provide sufficient room for the flame, or vice versa, to make the flame sufficiently short so that all of the fuel present in the powdered fuel mixture will be completely burned before the flame has reached the end of its path of travel.

It is accordingly the main object of my invention to overcome these difficulties and to provide a method of burning pulverized fuel which may be used for fuel mixtures correctly proportioned for perfect combustion and which will permit the formation of a short flame close to the burner or point of introduction of the fuel mixture into the furnace and insure the complete combustion of the fuel in the limited space devoted to this purpose.

A further object is to provide a method of burning pulverized fuel mixed with sufficient air for complete combustion which prevents the flame from striking back through the burner and yet insures the flame starting closely adjacent to the burner.

With these and other objects in view as will be apparent in the following disclosure, my invention resides in the steps of the method set forth in the specification and covered by the claims appended hereto.

Referring to the drawings, in which like reference numerals indicate like parts:

Fig. 1 is a sectional and interior view of a furnace and fuel burner, partly broken away;

Fig. 2 is an enlarged sectional detail showing the operation of the burner;

Fig. 3 is an interior view of the furnace front; and

Fig. 4 is a section on the line 4—4 of Fig. 3, partly broken away.

In accordance with my discovery, I have found that if the burner is so constructed and the process of combustion is so carried on that a rich mixture of powdered fuel and air is introduced at one point in the burner adjacent to the leaner mixture, the latter will be ignited due to the fact that the flame will be propagated back through the rich mixture to a point adjacent to the burner. Or, if jets or eddies of a slowly moving fuel mixture are formed in the rapidly moving stream of fuel and air, the flame will strike back to a point where the fuel is traveling ahead faster than the rate of flame propagation. This serves to form pilot lights, as it were, close to the burner and intimately in contact with the rapidly traveling lean mixture of fuel and air.

One feasible way of securing this ideal result is to provide a mixture of powdered fuel and air in correct proportions for complete combustion of the fuel and to pass this mixture into the furnace at a rate greater than that of the flame propagation to prevent the flame from striking back into the burner, and forming a localized zone of rapid flame propagation, by means of a baffle, grid or the like, which causes the formation of a pilot flame close to the burner capable of lighting the main rapidly moving stream of fuel.

Referring to the drawings illustrating a portion of a furnace and one simple construction adapted for carrying out this invention, a jet of uniformly mixed air and fuel may be passed into the furnace from any suitable source through a pipe 10 of substantially uniform and rectangular cross section. The fuel mixture is preferably passed first into a small expansion chamber 11 formed in the front wall of the furnace and thence into the combustion chamber proper of the furnace. At the point where the fuel issues from the pipe 10 into the expansion chamber, I provide a grid or series of baffles 12 so constructed and positioned as to obstruct the flow of the gas and fuel mixture. The expansion chamber flares inwardly as illustrated so as to provide for the increasing volume of gas, and the fuel inlet pipe preferably inclines downwardly so as to direct the flame towards the bottom of the furnace.

The baffles illustrated comprise strips of

metal having plane rectangular faces of considerable width. Two of these baffles have been used in one installation in a horizontal position, as illustrated in Figs. 1 and 2, where the inlet pipe is inclined downwardly. I prefer to mount them as shown in Fig. 4 so that they be separately adjusted to different angles by means of the damper handles 14 fastened thereto and projecting through a slot 15 suitably formed in the furnace wall. This permits one to spread the flame and give it a desired length of travel, as well as to fill the furnace with the flame, if desired, and to control the condition of the slag formed by burning the fuel. The arrangement of baffles illustrated in Fig. 4 permits one to spread the flame. The adjustability of the baffles is particularly desirable if the furnace construction and the nature of the coal are such as to be conducive to the formation of slag. For example, if the burner pipe is directed downwardly and the flame would ordinarily strike the floor and so melt the light ash and form a slag, the baffles may be adjusted to position the flame higher in the furnace and prevent slagging the ash, or the shape of the flame may be changed to that found most effective.

While I do not care to limit this case to any particular theory of operation, and it of course is impossible to observe what is happening within the furnace, it is my belief that these baffles cause fuel particles to become segregated from the uniform mixture and to spill over the edges of the baffles in thin sheets, as light snow blows from a roof. It may be, however, that the frictional retardation of the baffle on the mixture slows down the rate of travel of these thin fuel streams. However, these streams of concentrated fuel or slowly moving bodies tend to ignite easily and more rapidly than the leaner mixture of the surrounding cloud of air and fuel, and insure a high temperature or a pilot flame nearer the inlet pipe than is obtainable if the baffles are not present. Consequently the flame strikes back into this territory adjacent the fuel burner and in the expansion chamber. The heat of these pilot flames causes the gas immediately around them to expand and to ignite in this chamber and consequently by the time the fuel has reached the combustion chamber of the furnace it is burning fully.

I moreover preferably so form this grid or baffle construction that it will be self-cleaning and capable of being protected from the intense heat of the furnace. This is ordinarily insured by making the upper surfaces thereof smooth. The baffles are spaced apart sufficiently so as not to obstruct seriously the introduction of fuel into the furnace. While it is feasible to use water-cooled baffles, I preferably so locate

the baffle or grid construction that the incoming mixture of gas and fuel will keep the grid cool and prevent its destruction.

It will be readily understood from the above disclosure that various other arrangements may be utilized within the scope of the claims appended hereto. It will also be understood that this baffle construction is not intended to be used with an imperfect mixture of fuel and air, in order to give a more uniform mixture, but it is employed with a fuel and air body which has the desired uniformity of composition, and is intended to destroy locally that uniformity and to segregate fuel particles from the incoming mass. The fuel may be mixed previously in a construction of the type shown in the reissued patent to Blyth, No. 16,229 of Dec. 15, 1925.

Having thus described my invention, what I desire to secure by Letters Patent and claim as new, is:—

1. The method of burning pulverized fuel comprising the steps of feeding through a burner to a combustion chamber a supply of pulverized fuel and air which are intimately mixed and proportioned for complete combustion of the fuel, while maintaining a rate of fuel movement through the burner sufficiently greater than the rate of flame propagation to prevent the flame from striking back into the burner and such as would normally cause the flame to burn only at a distance from the burner, causing the fuel mixture to issue rapidly into and expand in a large combustion space, and maintaining a localized fuel zone in the fuel stream in said combustion space but adjacent to the burner which has a more rapid rate of flame propagation than the major portion of the fuel stream and sufficient to cause said major portion to start burning close to the burner.

2. The method of burning pulverized fuel comprising the steps of feeding to a furnace burner a supply of pulverized fuel and air which are intimately mixed and proportioned for complete combustion of the fuel, while maintaining a rate of fuel movement through the burner sufficiently greater than the rate of flame propagation to prevent the flame from striking back into the burner and such as would cause the flame to burn only at a distance from the burner, and causing a small portion only of the fuel mixture, as it enters the combustion space, to contact with an extensive surface arranged at an angle to and in the path of the stream to provide a restricted zone of rapid flame propagation near said surface which burns close to the burner and ignites the main stream of fuel and air and causes it to burn close to the burner.

Signed at Worcester, Massachusetts, this 2nd day of March, 1925.

L. V. ANDREWS.
